FUEL BURNER

Charles E. Lucke, New York, N. Y., assignor to
 Fuller Lehigh Company, Fullerton, Pa., a corporation of Delaware

Application November 14, 1930, Serial No. 495,561

2 Claims. (Cl. 110—28)

This invention relates to a fuel burner by means of which fuel in suspension in primary air is projected into a furnace. By the present invention hot secondary air, even up to the temperature of ignition of the fuel, can be introduced into the furnace, together with the primary air and fuel and the burner nozzle is protected from the intense heat.

The invention will be understood from the description in connection with the accompanying drawings in which Fig. 1 is a horizontal section through an illustrative embodiment of the invention; Fig. 2 is a similar section through a modification of the nozzle extension; Fig. 3 is a section along the line 3—3 of Fig. 4 showing a modification; Fig. 4 is a vertical section along the line 4—4 of Fig. 3 and Fig. 5 is an elevation viewed from the inside of the furnace as indicated by the line 5—5 of Fig. 3.

In the drawings there is shown a fuel burner 1, through which primary air and fuel, for example pulverized coal, is projected into a furnace. A wall of the furnace is shown made up of a row of water wall tubes 2 and tile 3 that are attached to the tubes.

A secondary air casing 4 is provided into which heated secondary air is introduced and then passes into the furnace along opposite sides of the stream of fuel and primary air. The casing 4 is provided with a lining of heat insulating material 5. The casing 4 is provided with inclined plates or partitions 6 leaving a space 7 for cooling fluid, for instance, air that is approximately triangular in cross section.

A nozzle extension 8 is provided inside the casing 4 at the exit end of the burner 1. The nozzle extension 8 is provided with ribs 9 to aid in keeping the same cool by contact with the air that is passed through the space 7.

Two of the tubes 2 that are indicated by the reference character 10 are bent outwardly where the end of the nozzle 8 is located to extend beyond the plane of the other tubes 2. Staggered blocks or tile 11 are located in the spaces between the bent portions 10 of the tubes and the adjacent tubes 2, thus providing staggered openings 12 from opposite sides of the air casing 4, so that the staggered streams of hot secondary air from this casing impinge against opposite sides of the stream of fuel and primary air entering from the nozzle extension 8. It will be evident that the blocks are staggered in such a manner that the secondary air-ports or openings are disposed at alternate elevations on either side of the fuel nozzle. The end of the nozzle exten-

sion 8 is provided with rounded portions 13 to fit closely against the tubes 10 and the opening through the nozzle extension 8 is so shaped that a wide, thin stream or sheet of fuel and air passes through the long, narrow outlet 14 between the tubes 10 and parallel thereto. It will be clear that the construction just described permits the use of secondary air of extremely high temperature and even a temperature above the coking point of the fuel used. By cooling the fuel nozzle coking 10 therein is prevented.

In the modification shown in Fig. 2 the opening 15 through the nozzle extension 8 is made of sinuous form with a straight extension at its exit so that radiant heat from the furnace will be 15 prevented from reaching the rear portion thereof.

By providing the space 7 in the casing 4 a cooling fluid such as air can be passed through this space to cool the nozzle extension 8 in addition to the cooling effect of the tubes 10 that are in 20 contact with the end thereof. The air that is heated thereby may be passed to the furnace for combustion purposes.

In the modification shown in Figs. 3, 4 and 5 the fuel burner 16 extends into contact with the 25 tubes 10 and the portion within the casing 4 is surrounded by a water jacket 17, the top of which opens into the casing 4, as indicated at 18 (Fig. 4) so that any vapors that may be generated in the jacket 17 can pass into the secondary air 30 casing 4 and thence into the furnace. A valve inlet pipe 19 is provided for supplying water to the jacket 17. An overflow 20 is provided near the upper end of the jacket 17 and a valved drain pipe 21 is provided at the bottom thereof.

Condenser circulating water may be circulated through the jacket 17 or a fixed water level may be kept in this jacket by supplying merely the amount of water that is evaporated therefrom. Of course a sinuous nozzle may be used in this 40 modification as well as the other one to stop radiant heat from reaching the rear portion of the fuel passage.

By this invention the nozzle is not only protected against the heat from the hot secondary air, but is also protected against heat radiated from the furnace, so that when carbonizing coal is used the passage therefor will not become clogged up. The nozzle itself is also protected from the heat, thus avoiding distortion, cracking or burning the same. By thus protecting the nozzle itself secondary air of extremely high temperature may be employed, thus securing the advantage of shorter flame and more efficient com- 55

bustion than can be realized with other constructions.

I claim:

1. In a furnace having a wall, a fuel burner nozzle arranged to project primary air and fuel through said wall in the furnace, a casing for secondary air, said nozzle extending through said casing, a tube in the furnace wall in contact with the end of said nozzle for cooling the same, a jacket for cooling fluid surrounding said nozzle, and ribs on said nozzle extending outwardly therefrom into said jacket for contacting with the cooling fluid therein to cool said nozzle.
- 5
- 10

2. In a furnace wall having a fuel burner port formed therein, a wall cooling tube extending across said port, a fuel burner nozzle arranged to discharge through said port and having its discharge end contacting with and cooled by said wall tube, a conduit for high temperature air for combustion at one side of said nozzle and opening to said port adjacent said nozzle, and a cooling fluid jacket surrounding said nozzle and positioned between said air conduit and said nozzle.

CHARLES E. LUCKE.

CERTIFICATE OF CORRECTION.

Patent No. 2,008,671.

July 23, 1935.

CHARLES E. LUCKE.

It is hereby certified that error appears in the printed specification of the above numbered patent requiring correction as follows: Page 1, first column, line 33, after "air" insert a comma; and page 2, first column, line 6, claim 1, for "in" read into; and that the said Letters Patent should be read with these corrections therein that the same may conform to the record of the case in the Patent Office.

Signed and sealed this 26th day of November, A. D. 1935.

(Seal)

Leslie Frazer
Acting Commissioner of Patents.
